UNITED STATES PATENT OFFICE.

HENRI RUSCH, OF ST. LOUIS, MISSOURI.

REINFORCED CONCRETE CONSTRUCTION.

1,111,972.

Specification of Letters Patent. Patented Sept. 29, 1914.

Application filed August 8, 1913. Serial No. 783,844.

To all whom it may concern:

Be it known that I, HENRI RUSCH, a citizen of the United States, residing at St. Louis, Missouri, have invented a new and useful 5 Reinforced Concrete Construction, of which the following is a specification in such full, clear, and exact language as will enable those skilled in the art to which the invention relates to comprehend the invention.

10 This invention relates to reinforced concrete construction, and it has for an object the provision of a system of concrete construction including a floor and a series of beams integrally united to form a monolithic structure, and provided with a novel and superior form of metallic reinforcement whereby the concrete is strengthened, and whereby the plaster laths may be supported.

Another object is to provide an improved 20 concrete floor construction including a concrete floor and a number of concrete beams having monolithic connection with the floor, in combination with a metallic reinforcing plate extending along the lower edge of each 25 beam, and a number of reinforcing arms rigidly connected with said plate and embedded in the beams effectively to transmit all stresses from the plate and other reinforcements into stronger portions of the concrete beams.

30 A further object is to provide a concrete floor construction comprising a number of concrete beams provided with metallic reinforcements, and means in connection with said reinforcements for supporting the laths and the plaster.

Other objects will appear from the following description, reference being made to the accompanying drawings in which I have 40 illustrated one embodiment of the invention, and in which—

Figure 1 is a plan view of a series of forms adapted for use in producing floors in accordance with my invention, illustrating 45 the reinforcing elements supported by and engaging with the forms before the placing of the concrete. Fig. 2 is a sectional view, enlarged with respect to Fig. 1, and may be considered as taken on the line 2—2 of Fig. 50 1. Fig. 3 is a side elevation of one of the reinforcing plates before being placed in connection with the forms. Fig. 4 is a sectional view, approximately on the scale of Fig. 2, illustrating the completed structure, 55 including the lath material, the means for attaching the lath material to the beams and

reinforcement, and the fire-proof plaster supported by the lath material to protect the lath material and reinforcing plate from fire, etc. Fig. 5 illustrates one of the forms 60 being removed from the structure after the concrete has hardened. Fig. 6 is an enlarged end elevation of one of the reinforcing plates. Fig. 7 is a longitudinal sectional view of a portion of one of the reinforcing plates.

The walls 1 may be of any suitable incombustible material, and the construction thereof is immaterial. The specific structure of the walls constitutes no part of the 70 present invention.

In erecting structures embodying my invention I utilize forms of suitable construction and arrangement, and, in the embodiment shown, each form consists of a frame 75 of strong construction, with a sheet metal wall, and accessories for holding the form in proper shape and for co-operatively engaging the reinforcing elements. The frame of each form consists of the pivotally united 80 angle iron frame parts 2, the frame parts on opposite sides of the form being pivoted by bolts 3 which pass through overlapping parts of the angle irons. The lower ends of the frame parts are connected and braced by 85 a cross-member 4, held in position by bolts 5 which are removable in order to permit compression or reduction of the forms so that they may be removed after the concrete has hardened. The frame parts support the 90 form walls 6 which, in the form shown, are of corrugated sheet metal, but which may be of any other suitable construction according to preference.

In constructing floors a number of forms 95 are arranged end-to-end in a longitudinal series, as shown in Fig. 1 in which the longitudinal series A consists of three forms arranged end-to-end between the walls 1. Other longitudinal series of forms B, C, and 100 D, etc., are similarly arranged, the several series being parallel and substantially equally spaced. The forms may be supported by any suitable means, such, for instance, as by posts and struts, the use and arrangement of 105 which are too well known to require illustration or description. Each form supports two angular plates 7 which extend laterally from the lower edges thereof. The plates on the several forms of each series abut end-to-end when the forms are assembled for use. The plates 7 are provided with a number of

holes 8 which are preferably spaced equal distances apart so that the reinforcing plates may be readily placed in position and interlocked with the several series of forms.

5 The reinforcing plates are positioned between adjacent series of forms before the concrete is placed upon or between the forms. Each reinforcing plate 9 is cut to form a number of flexible portions 10 which, 10 when bent laterally at right angles to the plate, constitute projections which will extend through the holes 8 in the plates 7, and thereby lock the forms of each series to the forms of adjacent series. The plates 9 thus 15 close the lower parts of the spaces between adjacent series of forms, and constitute supports for the concrete between adjacent series of forms. A number of flexible arms or any other kind of shear reinforcements 20 are rigidly attached to the upper side of each plate 9, and when originally attached may lie flat upon the plate 9, but when said plate is positioned, and before the concrete is placed thereon, said arms are 25 bent or flexed to position substantially as shown in Figs. 3 and 7, that is at a suitable angle, preferably obliquely, with respect to the plate. Preferably these arms are arranged in rows, and the arms of each row 30 are closest together near the ends of the plate and are separated by gradually increasing distances toward the middle of the plate, as illustrated in Fig. 3. Relatively a considerable part of each plate about equidistant 35 from the ends thereof is not provided with arms, so that the stress at the central portion is transmitted to the structure near the ends of the plates which are also near the ends of the beams. After the plates 9 have 40 been locked in position, and after the arms 11 have been bent to the position required, a quantity of concrete, say a layer about one inch in depth, more or less, is placed between adjacent series of forms upon each of 45 said plates, and the reinforcing rods 12 are placed upon said layer of concrete between the rows of arms 11, after which the remainder of the concrete is placed between and upon the forms, so as to form the floor 50 monolithically with the beams. Above the forms a reinforcement 13, preferably of woven wire, is embedded in the floor structure below the ends of the arms 11. The 55 surface of the floor is finished a slight distance above the ends of the arms 11. After the concrete has hardened the forms are removed by releasing one end of the brace connections 4, and slightly reducing the distance or dimensions between the sides of the 60 forms, as shown in Fig. 5.

After the forms have been removed the metal lath 14 is placed against the lower sides or edges of the beams, and the projections 10, which extend through the openings in the lath material, are clamped under

the lath material, thereby rigidly locking or uniting the lath material with the reinforcement and with the beams. The incombustible plaster may then be applied in the usual manner and to any desired thickness.

70 From the foregoing it will be seen that the plates 9, which constitute part of the reinforcement for transmitting all of the stresses into the end portions of the concrete beams, are utilized in connection with the forms to hold the concrete during the formation of the structure; and that, in addition to subserving their functions as supports for the concrete during the formation of the structure and as reinforcements for the concrete after the structure is completed, said plates also interlock with and hold the forms in proper position during the formation of the structure. Attention is also invited to the fact that, after the concrete structure 75 has been formed, the metal lath is locked or united with the reinforcements by means of the projections 10, and that all of the reinforcements are protected and shielded from fire, etc., by the incombustible plaster.

90 I am aware that there may be various modifications of my invention, as well as changes in the arrangement of the parts, without departure from the spirit and scope of the invention. It will be understood that 95 I contemplate such modifications and changes as will completely adapt the invention to various requirements and preferences. What I claim and desire to secure by Letters Patent of the United States is—

100 1. The combination with a concrete beam, of a metal plate bonded to the exterior lower side of said beam by the hardening action of the concrete, means on said plate for engaging the forms which shape the side surfaces of said beam during the formation of the beam, a plurality of obliquely disposed arms embedded in the concrete and having their lower ends rigidly united with said plate, and a rod separate from said plate 105 embedded in the concrete above said plate and separated from said plate by a layer of concrete, substantially as described.

110 2. The combination with a concrete beam, of a metal plate bonded to the exterior lower side of said beam by the hardening action of the concrete, means on said plate for engaging the forms which shape the side surfaces of said beam during the formation of the beam, a plurality of arms between the 115 side edges of said plate embedded in the concrete and rigidly united with said plate, and a rod separate from said plate embedded in the concrete between said arms above said plate and separated from said plate by 120 a layer of concrete, substantially as described.

125 3. The combination with a series of concrete beams monolithically united with each other, metal plates of equal width with the 130

lower sides of said beams bonded against the exterior lower sides of said beams by the hardening action of the concrete, a row of arms rigid with said plates near each side 5 edge thereof and embedded in the concrete, projections rigid with said plates, and metallic lathing supported by said projections between said plates, substantially as described.

10 4. The combination with a series of monolithically united concrete beams, a metallic plate of equal width with the under side of each beam bonded against the exterior under side of said beam by the hardening action 15 of the concrete, parallel rows of arms rigid with said plate and embedded in said concrete, rods embedded in said concrete between said rows of arms and separated from said plate by a part of the concrete, and projections rigid with said plates for the purpose set forth, substantially as described.

5. The combination with a series of monolithically united concrete beams, a metal plate of equal width with the lower side of each beam bonded against the exterior lower 25 side of each beam by the hardening action of the concrete, rows of arms rigid with each plate and embedded in the concrete, rods embedded in the concrete parallel with each plate and separated from each plate by 30 a layer of concrete, projections integral with said plates, metallic lathing between said plates engaged and supported by said projections, and plaster supported by said lathing, substantially as described. 35

In witness whereof I have signed this specification in the presence of two subscribing witnesses this 6th day of August, 1913.

HENRI RUSCH.

In the presence of—

JOHN T. CRAVEN,
J. D. RIPPEY.
